UNITED STATES PATENT OFFICE

ANDERS JOHANSSON, OF STACKEBO-HED, SWEDEN, ASSIGNOR TO WESTINGHOUSE ELECTRIC & MANUFACTURING COMPANY, A CORPORATION OF PENNSYLVANIA

CONTROL APPARATUS

Application filed November 19, 1927. Serial No. 234,422.

My invention relates generally to control apparatus and more particularly to time-limit, snap-action switches.

The object of my invention generally stated 5 is to provide a simple and reliable mechanically-operable limit-switch.

It is also an object of my invention to provide for positively actuating a switch at predetermined intervals.

10 A further object of my invention is to provide for effectively lubricating the actuating mechanism of a mechanically operable time-limit switch.

15 Another object of my invention is to provide for free movement of the driving element of a limit-switch in the direction in which the switch is actuated without further actuation of the switch.

20 Other objects of the invention will, in part, be obvious and will, in part, appear hereinafter.

The invention accordingly is disclosed in the embodiment thereof shown in the accompanying drawings and comprises the structural features, the combination of elements and arrangement of parts which will be exemplified in the construction hereinafter set forth, and the scope of the application which will be indicated in the claims.

25 For a more complete understanding of my invention, reference may be had to the following detailed description taken in conjunction with the accompanying drawings, in which:

30 Figure 1 is a sectional view in side elevation of a limit-switch constructed in accordance with my invention and showing the relative positions of the different members,

35 Fig. 2 is a view in end elevation of the switch showing the snap-action mechanism, and

40 Fig. 3 is a cross-sectional view taken along the line III—III of Fig. 1.

45 Figs. 2, 4, 5, 6, 7 and 8 show the various positions of the snap action mechanism when it is actuated in one direction and the operation of the switches may be readily understood from an examination of them.

50 As illustrated a casting or frame 1 is provided to carry the switching mechanism, as

well as other apparatus. A shaft 2 for carrying the contact members is pivotally mounted in the frame in bearings 3 and 4. A plurality of arms 5 to which contact members 6 are attached are mounted on the shaft 55 2 and the contact members 6 are disposed to cooperate with resiliently supported contact members 7 carried by the frame.

In order that the switch arms 5 may be moved or actuated with a snap motion an 60 over-center spring snap action mechanism for operating the switch is provided.

For the purpose of maintaining positive contact pressure between the contact members 6, carried by the arms 5, and the contact members 7, until the over-center spring snap action mechanism is actuated through its position of unstable equilibrium, springs 7' are provided. As is shown, the springs are maintained in compression when the contact members 6 and 7 are closed (see Fig. 3). When the contact arms 5 are actuated in a counter-clockwise direction, as viewed from Fig. 3, the springs 7' will cause the contact members to turn about the shafts 8', whereby positive contact pressure will be maintained between the contact members 6 and 7 until the switch arms 5 have been actuated with a snap motion. The snap motion results as a consequence of the over-center spring mechanism being actuated through its dead-center or position of unstable equilibrium.

As will be observed, the contact members 6 and 7 are so shaped, that rolling contact is effected between them during both the closing and opening operations of the switch mechanism.

With a view to oscillating the shaft 2 carrying the contacts 6 a lever arm 8 is provided, to one end of which a spring 9 is attached by means of a link 10. The other end of the spring is connected by a link 11 and a bolt 11a to a pivot crank member 12. In 95 order to facilitate easy pivotal motion between the link 11 and the pinion 11a a roller bearing member 13 is provided as illustrated.

The crank member 12 is pivotally mounted on a shaft 14, which in turn is loosely mounted in a bifurcated lever member 15 that is 100

5 pivotally supported on the main operating shaft 16 of the traveling nut device. Where the shaft 14 is supported by the lever member 15, for the purpose of reducing friction, a pair of ball bearing members 17 are utilized, and in this particular switch are held in place in the manner illustrated.

10 At the inner end of the crank member is a jaw-like ratchet member 19 which is loosely mounted on the shaft 14 and disposed to engage the pawl 37 on the traveling nut device to move the spring biasing mechanism back and forth across the center line of the switch to cause the over-center spring 9 to actuate 15 the switch from one position to the other. The traveling or floating nut mechanism 31 is provided for actuating the spring biasing mechanism, and is adapted to be adjusted to regulate the number of revolutions of the shaft required for each operation of the switch mechanism.

20 The traveling or floating nut mechanism has a main operating shaft 16 which is supported in the frame 1 by the bearings 21 and 22 disposed at opposite ends of the shaft. The central portion of the shaft 16 is provided with a threaded section 20 on which is mounted a pair of traveling or floating nuts 23 and 24 for the purpose of actuating the 25 traveling nut device. The floating or traveling nuts are divided in order to give a wide range of adjustment to the traveling or floating nut mechanism.

30 At both ends of the threaded section 20 for the purpose of limiting the travel of the threaded or floating nuts 23 and 24, are firmly secured a pair of collars 25 and 26, respectively. Projections 27 and 28 are provided on the collars 25 and 26 to cooperate 35 with projections 29 and 30, disposed on the traveling nuts 23 and 24. In order to hold the traveling nuts 23 and 24 against rotation with the main threaded shaft 16, a guide member is provided which consists of a hollow cylindrical casing member comprising 40 an upper half section 32 and a lower half section 33, which are held together loosely on the shaft 16 by the bolts 34. The casing sections 32 and 33 are disposed to incase the collars 25 and 26, the traveling nuts 23 and 24 and the threaded section 20 of the shaft 16.

45 In the upper section 32 of the casing, a flange 35 is provided to engage in a groove 36 cut in the traveling nuts 23 and 24 to prevent them from rotating with the shaft 16.

50 The pawl member 37 which is provided to cooperate with the ratchet 19 is mounted in the left end of the lower casing section 33 as illustrated, and is rotated therewith. 55 A sprocket 38 is mounted upon the main actuating shaft 16 and may be driven through a drive chain or the like from a driving member (not shown). When the shaft 16 is rotated, the pawl 37 will be forced into engagement with the ratchet 19, when the cyl-

inder is retained against rotation. The force necessary to throw the spring biasing mechanism against the force of the tension spring 9 to one position or the other being greater than the friction encountered by the traveling nuts, the casing sections 32 and 33 will be held against rotation and the nuts 23 and 24 will travel back and forth upon the operating shaft 16 in a direction depending upon the direction of rotation of the shaft 16. 70 However, when one of the traveling nuts passes into engagement with one of the projections 27 or 28, on the stop collars 25 or 26, the casing will be held in fixed relation with the shaft 16. This will cause the casing or cylinder to rotate with the shaft 16, and the pawl member 37 will impart sufficient force to the ratchet member 19 to carry the spring biasing mechanism over the center of the switch and cause the spring 9 to snap 75 the contact lever arm 8 to its opposite position actuating the switching mechanism.

80 Should the element driving the operating shaft 16 continue to rotate in the same direction after the switch has been operated the pawl member 37 will merely strike the outer point 40 of the ratchet member 19 displacing the spring a slight amount, neither injuring the spring nor causing the switch to be further operated.

85 It will thus be seen that the driving mechanism can travel after operation of the switch, without causing injury to the snap action mechanism. Where my invention is employed for reversing the operation of a motor and the motor causes the casing carrying the pawl 37 to rotate more than once after the switch has been actuated, no damage will be caused.

90 Fig. 4 illustrates the ratchet 19 and pawl 37 in the position they take when one set of the switch contact members 6 are in engagement with one set of contact members 7. As the pawl 37 is caused to rotate, it will carry the ratchet member and the spring biasing mechanism to the right and move the spring 9 over its dead center point as illustrated in Figs. 5, 6 and 7, respectively. Positive rolling contact will be maintained between the contact members 6 and 7, because of the action 95 of the springs 7', until after the spring 9 has passed over its center point, or position of unstable equilibrium. (the center point is illustrated in Figs. 6 and 7). Immediately thereafter, through the force present in the tension spring 9, the switch will be actuated with a snap motion into its other circuit closing position.

100 In order to provide for automatic lubrication of the bearings 21 and 22, in which the ends of the shaft 16 are journalled, the cylinder comprising the half cylindrical sections 32 and 33 may be packed with a suitable lubricant. The lubricant may be forced into the cylinder through a grease cup 16' dis-

posed at one end of the shaft 16. Lubricant from the grease cup 16' may be forced into the cylinder through a passageway P extending along the end of the shaft from the grease cup and terminating in the casing or cylinder.

As the traveling nuts 23 and 24 move back and forth on the threaded portion 20 of the shaft 16, grease or lubricant will be squeezed out along the shaft to the bearings.

While I have illustrated and described a particular embodiment of my invention, it is intended that all matter herein set forth shall be interpreted as illustrative and not in a limiting sense, since manifestly the same may be considerably varied without departing from the spirit of the invention as set forth in the appended claims.

I claim as my invention:

1. In a switching device in combination, an over-center spring mechanism disposed to actuate a switch, and an actuating mechanism therefor comprising a rotatable shaft having a plurality of floating nuts threaded thereon, a pawl member disposed to actuate the spring mechanism, and a lost-motion device disposed for actuation by said floating nuts, when the floating nuts have traveled a predetermined distance, to operate said pawl.

2. In a switching device, in combination, a switch, an actuating member therefor, an operating mechanism comprising a rotatable shaft provided with screw threads, a hollow casing enclosing the operating shaft for containing lubricant, a lost-motion connection between the casing and the actuating member, and a plurality of floating nuts disposed on said shaft and having a lost-motion connection with reference to the casing and said shaft.

3. In a switching device, in combination, a movable switch, an operating shaft, a plurality of floating nuts threaded on the shaft, means for limiting the travel of the floating nuts with respect to the operating shaft, and a pawl for actuating said switch, said pawl being disposed for operation by the travel limiting means.

4. In a lost-motion mechanism, a rotatable shaft having a plurality of traveling threaded nuts mounted thereon, spaced stop members secured to the shaft, the stop members being disposed to engage the threaded nut, and means for changing the relation of the distance between said travelling nuts and the distance between said stop members, whereby the travel of said nuts, as limited by said stop members, may be adjusted the travelling nuts in predetermined adjusted positions with reference to the stop members.

5. In a switching device, in combination, a snap-switch yieldingly maintained in two operative positions, a rotary actuating member therefor and means for connecting the actuating member to the switch comprising a ratchet member for moving the switch to

either operating position and a pawl for actuating the ratchet member to one position when continuously rotated in one direction and actuating the ratchet to another position when continuously rotated the other direction.

6. In a switching device, in combination, an operating shaft, a floating nut threaded thereon, stopping means secured to the shaft for engaging the floating nut, a hollow demountable casing disposed to enclose said floating nut and stopping means and adapted to hold a quantity of lubricating material, means for filling the hollow casing with lubricant and means for permitting automatic lubrication of various parts of the device from the supply of lubricant in the hollow casing.

7. In a switching device, in combination, a snap-action switch having an over-center spring, a ratchet mechanism for moving said spring to operate the switch, a rotating pawl for actuating the ratchet and means for connecting the ratchet to the spring so that after the pawl has actuated the ratchet to operate the switch in one direction the pawl can continue to rotate in that same direction without further operating the switch.

8. In a traveling-nut mechanism, in combination, an operating shaft, a pair of adjustable threaded nuts mounted thereon, stopping means for holding the nuts from rotating with the operating shafts, means secured to the shaft for engaging said nuts after they have traveled a predetermined distance, and means for actuating either of the traveling nuts when they make any contact with the stops secured to the shaft.

9. In a switching device, in combination, a snap-action switch having an over-center spring, a pivotally mounted ratchet for displacing the spring to actuate the switch, a pawl for actuating the ratchet and a traveling-nut mechanism for actuating the pawl, the traveling-nut mechanism comprising an operating shaft having a pair of threaded nuts mounted thereon and adapted to be adjusted for predetermining the number of revolutions the operating shaft will make in either direction before actuating the pawl, a pair of stop members secured to the shaft for engaging the traveling nuts, a casing for carrying the pawl, said casing enclosing the traveling nuts and stops and disposed to hold the nuts against rotation with the operating shaft.

10. In a switch actuating device, in combination, a rotatable shaft, a pair of traveling nuts disposed on the shaft and having screw-thread engagement therewith, means for adjusting the nuts to a plurality of different positions with reference to each other, and means secured to the shaft for engaging the nuts when they have been actuated a prede-

terminated distance determined by the distance between said nuts.

11. In a quick-make and break switch, in combination, a plurality of pivotally mounted contact members, a plurality of movable contact members, over-center spring mechanism for actuating said movable contact members from one position to another through an intermediate position of unstable equilibrium with a snap motion, and means for maintaining positive contact pressure between said pivotally mounted and movable contact members until said movable contact members have been actuated through said position of unstable equilibrium.

12. In a switching device, a driving member rotatable about an axis, a driven member rotatable about the same axis as said driving member, a pair of nuts freely rotatable with respect to one of said members and threaded thereto, means for preventing rotation of said nuts with respect to the other of said members, stop members for limiting the axial movement of said nuts, a switch, an actuating element for said switch, and a lost-motion connection between said driven member and said actuating element.

In testimony whereof, I have hereunto subscribed my name this fifteenth day of

October, 1927.

ANDERS JOHANSSON.
